POWER DRIVE FOR SAWMILL SET WORKS

Perry Orr, Naches, Wash., assignor of one-half to
Stanus Orr, Naches, Wash.

Application January 19, 1944, Serial No. 518,905

3 Claims. (Cl. 74—220)

1

My invention relates to set works for sawmill carriages and has particular reference to a power drive for manipulating the set shaft which in turn drives the set works to advance and recede the knees.

An important object of the invention is to provide a power drive of the above mentioned character which is more accurate than steam and eliminates the drag caused by the transmission of the steam to the set works.

A further object of the invention is to provide a power drive of the above mentioned character which is lighter than the steam actuated power drive and will cost much less.

A further object of the invention is to provide a power drive of the above mentioned character having very little upkeep.

A further object of the invention is to provide a power drive of the above mentioned character which is accurate since there is no variation of speed as the same can be driven at a constant speed, thereby eliminating inaccuracies in the operation of steam operated power drives, due to the rising and lowering of the steam pressure.

A further object of the invention is to provide a power drive of the above mentioned character that can be attached to any Armstrong type of set works at a small cost and quickly, without necessitating discarding the old set works.

A further object of the invention is to provide a power operated mechanism of the above mentioned character, the operation of which can be controlled with a minimum effort upon the part of the operator.

Other objects and advantages of the invention will be apparent during the course of the following description.

In the drawings forming a part of this application and in which like numerals are employed to designate like parts throughout the same,

Figure 1 is a plan view of the power drive of the set works, embodying my invention,

Figure 2 is an end elevation of the same,

Figure 3 is a vertical section taken on line 3—3 of Figure 1,

Figure 4 is a vertical section taken on line 4—4 of Figure 3, and

Figure 5 is a diagrammatic view of the transmission included in the power drive.

In the drawings, wherein for the purpose of illustration is shown a preferred embodiment of my invention, a power drive is shown which is mounted at a suitable location upon the sawmill carriage. This power drive comprises a set shaft 55 under pressure from a coupling 38, having screw

2

10 journaled in stationary bearings 11, secured to the carriage. The numeral 12 designates a hub which is mounted upon the set shaft 10 to rotate therewith and this hub is rigidly secured to the set shaft by a key 13 or the like. The hub 12 cannot move longitudinally of the set shaft. The hub 12 has radial flanges 14, as shown in Fig. 3. The numerals 15 and 16 designate sprocket wheels, rotatably mounted upon the set shaft 10 and alternately locked to the hub 12 for rotation therewith, by hydraulic means, to be described. Each sprocket wheel is rigidly secured to a flange 17, carried by a hub 18, rotatably mounted upon the set shaft. Stop rings 19 are rigidly mounted upon the set shaft 10. A hydraulic flush device is connected with each sprocket wheel and flange 17, including a head 19', arranged between the flange 17 and the sprocket wheels and attached thereby by the bolts 20. This head has a drum 21 rigidly secured thereto. A coacting head 22 is arranged at the open end of the drum and is rigidly secured to the flange 14, for rotation therewith. As more clearly shown in Figure 4, shoes 23 are arranged within the drum 21 and are pivotally connected at their lower ends with pins 24, and these pins are secured to the head 22. The pins 24 are connected by a link 25. Pins 26 are also secured to the head 22 and extend through openings 27 formed in the shoes 23 and these openings are larger than the pins 26 to permit of the proper lateral movement of the shoes into clamping engagement with the drum 21, but to limit the inward swinging movement of the shoes. The shoes 23 are swung inwardly by a retractile coiled spring 28, connected therewith at 29.

At their free ends, the shoes 23 are provided with reduced extensions 30 which extend through openings 31, formed in the rubber ends 32 of a cylinder 33. Mounted within the cylinder 33 are plungers 34, having suitable packings. These plungers are arranged to engage the extensions 30 to move them outwardly and expand the shoes 23 so that they have clamping engagement with the drum 21. These extensions serve to support the cylinder 33 and hold the same in position. The plungers 34 are moved apart by a compressible coiled spring 36, which is weaker than the spring 28 but will prevent the plungers 34 from moving inwardly beyond limits. The cylinder 33 is provided at its center with a port or opening 37, Figures 3 and 4, and this port receives a fluid

threaded engagement with the side of the cylinder 33, as shown at 39.

As more clearly shown in Figure 1 a flexible hose 40 is connected with the coupling 38 to the left while a flexible hose 41 is connected to the coupling 38 to the right. The hose 40 and 41 have suitable slack and are positioned beneath the hub 12 and the hose 40 is connected with a pipe 42 while the hose 41 is connected with a pipe 43, by couplings 42' secured to a stationary bracket 43'. The pipe 42 leads to an upper horizontal cylinder 44 and is connected therewith while the pipe 43 leads to a lower horizontal cylinder 45. These cylinders are held stationary and are preferably arranged near the operator's seat 46. Plungers 47 and 48 are mounted to reciprocate within these cylinders and are connected with rods 49 and 50, respectively, having pivotal connection with an upstanding lever 51, at points above and below the pivot 52 of the lever. The pivot 52 is carried by a stationary support 53. The cylinders 44 and 45, upon the left side of the plungers 47 and 48, Figure 2, the pipes 42 and 43, the hose 40 and 41, and the cylinders 33 between the plungers 34 are filled with a brake fluid, such as oil.

The numeral 54 designates a motor, suitably mounted upon the sawmill carriage and having an armature shaft 55, carrying a sprocket wheel 56, Figures 1 and 5. This sprocket wheel is rigidly mounted upon the armature shaft 55 and is engaged by a sprocket chain 57, which engages the sprocket wheel 15. The lower run of the sprocket chain 57 passes about the upper side of a sprocket wheel 58, and drives the same. This sprocket wheel 58 is rigidly mounted upon a counter-shaft 59, journaled in stationary bearings 60. A sprocket wheel 61 is rigidly secured to the counter-shaft 59 and has a sprocket chain 62 passed about the same, which also passes about the sprocket wheel 16. As more clearly shown in Figure 5, the armature shaft 55 is turning counter-clockwise, while the counter-shaft 59 is turning clockwise. The shaft 55 therefore turns the sprocket wheel 15 counter-clockwise and the counter-shaft 59 turns the sprocket wheel 16 clockwise. The sprocket wheels 15 and 16 are therefore turning continuously in opposite directions.

In operation, the motor and associated gearing turns the sprocket wheels 15 and 16 continuously in opposite directions with relation to the set shaft 10, which is stationary, when the lever 51 is in the vertical or neutral position. The shoes 23 do not now have sufficient engagement with their drums 21, which are continuously rotating, to rotate the hub 12. To turn the set shaft 10 in the direction of the turning movement of the sprocket wheel 15, the lever 51 is forced inwardly, whereby the plunger 47 is forced forwardly while the plunger 48 is moved rearwardly. The brake fluid is therefore forced from the upper cylinder 44 and is transmitted to the cylinder 33 adjacent to the sprocket wheel 15, while the brake fluid within the cylinder 33 adjacent to the sprocket wheel 16 is free to move into the lower cylinder 45. The plungers 34 in the cylinder 33 adjacent to the sprocket wheel 15 are therefore moved apart and will act upon the extensions 39, forcing these extensions outwardly and expanding the shoes 23. These shoes will now have clamping engagement with the drum 21 next to the sprocket wheel 15 and head 22 will therefore be locked to the adjacent drum 21. The head

22 will now turn with the drum 21 and the head 22 will turn the hub 12 with the sprocket wheel 15 and the hub 12 will turn the set shaft 10. The set shaft is only turned for about $\frac{1}{3}$ of a revolution after which the lever 51 is returned to the neutral position and the shoes 23 moved out of clamping engagement with the adjacent brake drum 21. Turning movement of the head 22 to the left, Figure 3, provides further slack in the flexible hose 40 and 41. When the set shaft 10 is to be turned in an opposite direction with the sprocket wheel 16, the lever 51 is swung from the seat 46, Figure 2, and the plunger 48 moves forwardly and plunger 47 rearwardly. The brake fluid passes from the lower cylinder 45 into the cylinder 33 next to the sprocket wheel 16 and the shoes 23 next to the sprocket wheel 16 have clamping engagement with the adjacent brake drum 21. This drum now turns the head 22 in the direction of turning movement of the sprocket wheel 16, which turning movement is transmitted to the central hub 12 and set shaft 10. The set shaft 10 will now be turned with the sprocket wheel 16 for not more than $\frac{1}{3}$ of a revolution. This turning movement of the head 22 next to the sprocket wheel 16 takes up some of the slack in the hose 40 and 41, but this slack is again paid out when the lever 51 is returned to neutral position.

It is thus seen that the set shaft 10 will be turned in opposite directions, at the will of the operator, and that the force for effecting this turning movement is provided by the motor 54, and the operator is only required to manipulate the lever 51, which involves a relatively slight effort.

The set shaft 10 drives the set works in the usual manner and the knees are advanced or receded, depending upon the direction of rotation of the set shaft.

It is to be understood that the form of my invention herewith shown and described is to be taken as a preferred example of the same, and that various changes in the shape, size and arrangement of parts may be resorted to without departing from the spirit of my invention or the scope of the subjoined claims.

Having thus described my invention, what I claim is:

1. In a power drive for set works, a set shaft, wheels rotatably mounted upon the set shaft, means to drive the wheels in opposite directions, hydraulic clutch devices connected with the wheels and set shaft, each hydraulic clutch device including inner and outer units adapted to have clamping engagement with each other and to then both turn with the set shaft cylinders holding brake fluid, flexible tubes having slack and connecting the cylinders and the hydraulic clutch devices, plungers within the cylinders, a pivoted lever, and connections between the lever and the plungers and arranged upon opposite sides of the pivot of the lever.

2. In a power drive for set works, a set shaft, wheels rotatably mounted upon the set shaft, means to drive the wheels in opposite directions, drums secured to the wheels, a hub arranged between the wheels and mounted upon the set shaft to rotate therewith, heads secured to the hub to rotate therewith, expandible devices mounted upon the heads for engagement with the drums and turning with the set shaft when the set shaft turns, hydraulic devices to operate the expandible devices and mounted upon the heads to rotate therewith and means to supply a fluid under pres-

sure to the hydraulic devices including flexible tubes connected with the hydraulic devices and having slack.

3. In a power drive for set works, a set shaft, spaced wheels rotatably mounted upon the set shaft, means to drive the wheels in opposite directions, a hub arranged between the wheels and mounted upon the set shaft to turn therewith, a drum connected with each wheel to turn therewith, a head arranged adjacent to each drum and mounted upon the hub to turn therewith, a hydraulic device mounted upon each head to turn therewith and having a part to frictionally engage with the drum, flexible tubes disposed adjacent to the hub and separate from the hub and connected with the hydraulic devices, the flexible tubes having sufficient slack to permit of the turning movement of the hub, and means to

force fluid under pressure through the flexible hose.
